UNITED STATES PATENT OFFICE.

HEINRICH WILSING, OF BERNBURG, GERMANY.

MANUFACTURE OF BLEACHING LIQUIDS.

1,023,287.

No Drawing.

Specification of Letters Patent.

Patented Apr. 16, 1912.

Application filed September 28, 1910. Serial No. 584,296.

To all whom it may concern:

Be it known that I, HEINRICH WILSING, chemist, a citizen of the German Empire, and resident of Bernburg, Dukedom of Anhalt, Germany, have invented certain new and useful Improvements in or Relating to the Manufacture of Bleaching Liquids, of which the following is a specification.

My invention relates to a process for the manufacture of bleaching liquids by the action of chlorin on alkaline-lyes and consists therein that the chlorin either in the form of gas or in liquid state is introduced into a liquid which contains at the same time 10 alkaline-hydrate and alkaline-carbonate. This process results in the production of a bleaching liquid which contains as bleaching agents free hypochlorous acid in addition to hypochlorite of alkali. The proportion of such bleaching agents may be varied according to requirements by suitably proportioning the contents of the alkaline-lye in alkaline-hydrate and in alkaline-carbonate. 15

20 The reactions taking place may be seen from the following equations:

It appears that at first the chlorin converts the whole of the sodium-hydrate and that then in accordance with the equation 2 the conversion of the carbonate takes place. 25 Therefore in one single operation a bleaching lye is obtained which contains according to the proportion of carbonate to hydrate adopted a mixture of sodium-hypochlorite, free hypochlorous acid, sodium-bicarbonate, and sodium-chlorid. If as is advisable a 30 small portion of the alkali is left uncombined, it will remain in the lye in the form of carbonate.

The advantages of the invention are: great simplicity and easy control of the manufacture, high yield of active chlorin, high stability, and a proportion of free hypochlorous acid which can be regulated in accordance with the desired bleaching energy and the properties of the material to be bleached. Finally the presence of sodium-bicarbonate prevents the formation of

free hydrochloric acid from the hypochlorous acid during the bleaching process.

The stability of the bleaching liquid obtained in accordance with the invention appears from the fact that a liquid containing 17-32% of its active chlorin in form of free hypochlorous acid loses in 18 hours only 1-3% of its active chlorin, whereas it has 55 been found that electrolytic lyes which contain 21-5% of their active chlorin in the form of free acid lose in 18 hours 40-80% of their 60 total bleaching chlorin (compare Kind and Weindel, *Comparative Investigations of Chlorin Bleaching Lyes*, Leipsic, 1909, page 20).

The process may be carried through as follows: 50 kg. of chlorin are caused to act in a slow jet, and avoiding strong heating, 70 on three cubic meters of a diluted alkaline lye containing 34.2 kg. of hydrate of soda and 41.6 kg. of carbonate of sodium, in a suitable apparatus provided with a stirring device. The chlorin is easily and completely 75 absorbed, and 3.03 cubic meters of a bleaching liquid with 16.35 grams of bleaching chlorin per liter are obtained. Of the chlorin 60% in round figures are in the form 80 of sodium hypochlorite and 40% in the form of free hypochlorous acid. If desired, potassium carbonate and caustic potash can be used instead of sodium carbonate and caustic soda.

What I claim is:

1. A process for the manufacture of bleaching liquids by the action of chlorin on alkaline lyes consisting in introducing chlorin into a liquid containing alkaline hydrate with alkaline carbonate.

2. In a process for the manufacture of bleaching liquids by the action of chlorin on alkaline lyes containing alkaline hydrate with alkaline carbonate proportioning the alkaline hydrate to alkaline carbonate so 95 as to produce free hypochlorous acid in addition to hypochlorite of alkali in a proportion according to requirements.

In testimony whereof, I affix my signature in presence of two witnesses.

HEINRICH WILSING.

Witnesses:

HENRY HASPER,
WOLDEMAR HAUPT.
